US00D329441S

United States Patent [19]

Yee

[11] Patent Number: Des. 329,441

[45] Date of Patent: ** Sep. 15, 1992

[54] **MAGNETICALLY OPERATED
FRICTIONLESS BEARING ASSEMBLY**

4,794,290 12/1988 Nagasaka 310/90.5
4,959,568 9/1990 Stokes 310/90.5

[76] Inventor: Norman D. Yee, 955-14th Ave.,
Honolulu, Hi. 96816

Primary Examiner—Nelson C. Holtje
Assistant Examiner—Antoine D. Davis
Attorney, Agent, or Firm—Richard C. Litman

[**] Term: 14 Years

CLAIM

[21] Appl. No.: 379,906

The ornamental design for a magnetically operated
frictionless bearing assembly, as shown and described.

[22] Filed: Jul. 14, 1989

DESCRIPTION

[52] U.S. Cl. D15/143; D10/46;
D10/103; D15/138; D15/199

[58] Field of Search D15/199, 138, 199;
310/90.5; D10/46, 103

References Cited

FIG. 1 is a perspective view of a magnetically operated
frictionless bearing assembly showing my new design;
FIG. 2 is an elevational view, the converse side being
identical thereto;

FIG. 3 is a side elevational view, all other side eleva-
tional views being identical; and,

FIG. 4 is a cross-sectional view taken along line 4—4 in
FIG. 3 thereof.

FIG. 1 has been drawn on an enlarged scale with re-
spect to FIGS. 2—4.
